(57) **CLAIM**

The ornamental design for a vehicle front bumper, as shown and described.

DESCRIPTION

FIG. 1 is a front perspective view of a vehicle front bumper showing our new design;

FIG. 2 is a front view thereof;

FIG. 3 is a left side elevation view thereof the right side being a mirror image of that side shown; and,

FIG. 4 is a top plan view thereof.

The portions of the vehicle shown in broken lines are for illustrative purposes only and form no part of the claimed design.
